UNITED STATES PATENT OFFICE.

JOHN H. BECKER, OF PHILADELPHIA, PENNSYLVANIA, AND WARREN S. BELLOW, OF WORCESTER, MASSACHUSETTS.

SPARK-PLUG.

1,315,202.

Specification of Letters Patent. Patented Sept. 9, 1919.

Application filed September 5, 1917. Serial No. 189,734.

To all whom it may concern:

Be it known that we, JOHN H. BECKER, a citizen of the United States, residing in the city of Philadelphia, county of Philadelphia, and State of Pennsylvania, and WARREN S. BELLOW, a citizen of the United States, residing in the city of Worcester, county of Worcester, and State of Massachusetts, have invented certain new and useful Improvements in Spark-Plugs, of which the following is a specification.

Our present invention comprehends certain improvements in spark plugs which tend toward greater serviceability and increasing efficiency.

The most extensively used type of spark plug is provided with a porcelain core. Porcelain possesses high insulating properties as it gives uniform distribution to electrical strains and is peculiarly capable of withstanding extreme temperature changes from an extreme cold condition to an intensely hot one generated at the firing points of the plug upon the ignition of an explosive charge. Furthermore, porcelain is not, under firing temperatures, susceptible to expansive or contractive changes. Hence, it is almost universally used as an insulator for the central electrode of spark plugs.

An inherent objectionable characteristic of porcelain resides in the fact that it is brittle and most spark plug troubles are directly traceable to broken cores which produce gas leakage and short circuits under ordinary conditions of temperature and electrical tension. Furthermore, the breakage of porcelain cores of conventional plugs frequently happens as a result of externally applied blows or strains, accidentally directed against the extended exposed portion thereof, such as might happen upon the slippage of a wrench or a pair of pliers while applying the plug to the engine or the ignition cable to the plug. It is the purpose of our invention to minimize this liability of breakage and still retain the desirable and proven efficient characteristics of porcelain as an insulator at the effective igniting points of the plug.

To the accomplishment of this, we provide a composite or sectional core made of porcelain and fiber or other suitable non-brittle material. We have found in practice that a core of this nature when provided with a suitable gasket between the sections renders

a plug durable, gas-tight and efficient for the purpose for which it is intended.

In the accompanying drawings, we have illustrated by way of example certain preferable embodiments of our invention, in 60 which—

Figure 1 is a view in side elevation partly in section of a conventional spark plug embodying the features of our invention.

Fig. 2 is a sectional view of the composite core illustrated in connection with Fig. 1.

Fig. 3 is a view in side elevation of a different form of plug equipped with our improved composite core.

Fig. 4 is a cross sectional view of the same plug illustrating the arrangement and relative positioning of the parts.

Referring to Figs. 1 and 2 in detail, the composite core comprises sections 1 and 2. The lower section of the core is preferably made of porcelain and has fixedly mounted or embedded therein a central electrode 3, the lower extremity of which projects therefrom, terminating in proximity to the 75 grounded terminal 4 carried by the threaded nut or bushing 5. The upper extending and exposed section of the core is preferably made of fiber or other non-brittle material and is provided with a bore 6 for the accommodation of the upper extremity of the central electrode 3. This bore is of sufficient diameter to provide a comfortable sliding fit so that the plug may be readily assembled or disassembled should the occasion require. The lower extremity of the section is shouldered as at 7, so that a nut or a screw-threaded sleeve 8 is capable of engaging therewith to keep it in place through the screw-threaded engagement 85 90 with the nut 5 at 9.

Interposed between the sections 1 and 2 is provided an asbestos or other gasket 10, which will serve to make gas-tight the joint thus preventing the escape of compression or gas through the bore 6 or past the bushing or sleeve 8.

This gasket also serves as a cushion to relieve pressure from the porcelain section, and prevents its breaking under pressure 105 of the sleeve 8. Furthermore, it prevents undue heating of the adjacent lower extremity of the fiber section of the core.

Mounted upon the upper extremity of the core is a metal ferrule or cap 11 and there- 110

above is provided the usual binding nuts 12 or other suitable fastening device for the ignition wire, these devices being mounted upon the screw-threaded extremity of the central electrode or upon a part electrically connected therewith.

Referring to Figs. 3 and 4, the upper section of the core is provided with a series of radially arranged apertures 13 and the central electrode is of two-part construction providing auxiliary sparking points 14 positioned at the apertures so that the spark intensity may be observed by means of which the firing efficiency of the plug may be regulated through the proper adjustment of these auxiliary points as the upper section of the central electrode is adjustably mounted as shown. In this construction, the upper fiber section 1 of the plug is held against the gas-
ket 10 by swedging over the metal of the bushing 5 as at 15 in close contact with the shoulder 7 of the core.

While we have illustrated certain preferable embodiments of the principles of our invention, we do this in an illustrative rather than in a definitive sense, desiring it to be understood that we wish to cover said principles in whatever form they may be embodied.

Having thus described our invention, what we claim as new herein and desire to secure by Letters Patent is:

1. A composite core for spark plugs, in-

cluding a porcelain end portion, an electrode extending through the porcelain end portion and rigid therewith, and a fiber shank portion loosely slideable on the electrode and normally held rigidly with the porcelain end portion.

2. A composite core for spark plugs, in-
cluding a porcelain end portion, an electrode extending through the porcelain end portion and rigidly embedded therein, a fiber shank portion loosely slideable on the electrode, the adjacent ends of the porcelain and fiber portions being cut off square, a packing washer between the said square ends, and means for clamping the porcelain and fiber portions rigidly together.

3. A composite core for spark plugs, in-
cluding a porcelain end portion, an electrode extending through the porcelain end portion and rigidly embedded therein, a fiber shank portion loosely slideable on the electrode, means for clamping the porcelain and fiber portions rigidly together, and a second electrode member fitted adjustably in the fiber shank portion and terminating in a spaced relation to the end of the first mentioned electrode to provide an auxiliary spark gap, the fiber shank portion being transversely apertured at the point of the auxiliary spark gap.

JOHN H. BECKER.
WARREN S. BELLOWES.
